UNITED STATES PATENT OFFICE.

JOHN B. WATLING, OF CHICAGO, ILLINOIS.

DESIGN FOR A CASING FOR A WEIGHING-SCALE.

51,403.

Specification for Design.

Patented Oct. 16, 1917.

Application filed August 17, 1917. Serial No. 186,810. Term of patent 14 years.

To all whom it may concern:

Be it known that I, JOHN B. WATLING, a citizen of the United States, and a resident of Chicago, county of Cook, and State of Illinois, have invented a new, original, and ornamental Design for Casings for Weighing-Scales, of which the following is a specification, reference being had to the accompanying drawing, forming a part hereof.

In the drawings, Figure 1 is a perspective

view of a casing for weighing scales showing my new design. Fig. 2 is a horizontal section on the line 2—2 of Fig. 1.

I claim:—

The ornamental design for a casing for a weighing scale, substantially as shown.

JOHN B. WATLING.
